CROSS ROLLING MILL

Samuel E. Diescher, Pittsburgh, Pa., assignor to
Diescher Tube Mills, Inc., Beaver Falls, Pa., a
corporation of Delaware

Application April 15, 1942, Serial No. 439,019

19 Claims. (Cl. 80—13)

This invention relates to cross-rolling mills of that kind in which a pair of rotary guide discs (or in some cases a single disc) engage the workpiece as it is rotated and advanced between a pair of helically-acting skewed reducing rolls, commonly termed cross-rolls. Cross-rolling mills of this kind are shown in the S. E. Diescher Patents Nos. 1,586,975, 1,870,209, 2,031,761, and 2,042,832.

The object of the invention is to provide a cross-rolling mill of this kind in which the working parts may be held in their relative positions with such rigidity as to provide maximum accuracy of gauge or wall thickness of product as well as maximum life of work engaging members.

The requirements of accuracy in maintenance of positioning of the working parts are especially exacting when thinner wall product is being made. For example, a tube specified to have a wall thickness of 15 gauge, i. e., 0.720", may actually become 14 gauge, i. e., 0.6830", if at a less heated portion of a workpiece the main rolls be forced 0.011" from their normal positions. Such a spread would be drastic, but at that it may occur at the end of the passage of a tube, the rearmost part of which may have become chilled. Even a lesser spread than this may lead to crowding of the steel between the main roll and its companion guide disc, which would mar the lip of the guide disc groove and perhaps also the face of the main roll. Such cases involve shut-downs for renewal of working members.

In the operation of such mills, whether piercing mills, for producing tubular blanks, or hollows, from cylindrical workpieces, or tube reducing mills for reducing the wall thickness of and elongating tubular blanks, it is highly desirable, in order to obtain uniform diameter and wall thickness, and also smooth surface product, and to avoid excessive wear on parts of the mill, and especially on the work-engaging surfaces of the guide discs and rolls and of the side edges of the discs, that both the guide discs and the rolls shall maintain their positions during the rolling operation without give or any weaving motion or vibration. The rolls and guide discs are driven at a comparatively high R. P. M., and the work-engaging surfaces of the guide discs move at correspondingly high speed in pressure contact with the rapidly rotating and longitudinally advancing workpiece. Under the high pressure to which they are subjected, the reducing rolls tend to back away from the pass line, and the guide discs, under the force exerted on them by the rapidly rotating workpiece, tend to move axially from their normal and proper positions; and if such

movements are permitted by the mountings of the rolls and discs, a harmful weaving movement thereof results. Such in and out motion of the rolls and axial motion of the discs, when the discs are set, as they should be, with close clearance between a peripheral edge thereof and one of the cross-rolls, leads to harmful spreading between the discs and the rolls and to undue wear of the work-engaging faces of the discs and rolls which in turn results in impairment of the surface finish of the product. Give, or yielding, in the mountings of the rolls and discs may result from slight flexibility in parts of the machine and from clearances between machine parts taken up as load is applied, and with workpieces that are not uniformly heated there will be such give to a harmful degree in spite of great care and accuracy in the design and construction of the mill.

A difficulty of the kind referred to has been due to failure of the guide discs to resist under operating pressures slight displacement from their adjusted positions. Such displacement of the guide discs is prevented according to the present invention, and maintenance of their position bearing steadily on the workpiece between the cross-rolls attained, by the provision of means whereby preloading pressure is applied to the disc shafts sufficient to take out all clearances and harmful yields in the shaft mounting parts. It is desirable in a mill according to the present invention, that the cross-rolls shall also be preloaded to take up clearances and harmful yields. Cross-rolling mills of the kind to which the invention relates have been equipped heretofore with means for partially so preloading the cross-rolls, and no claim is, therefore, made in this application to such partial preloading of the cross-rolls per se. Disc preloading according to the invention may, of course, be employed to advantage without the preloading of the main rolls, that is, the cross-rolls, but for best results it is desirable that both discs and main rolls shall be preloaded.

The preloading of both the main rolls and the guide discs should be of such effect that with normal variations of temperatures of the workpiece and normal variations of loading of the work members no change from their relative idle positioning occurs. It will be readily understood that in adjusting a guide disc to its correct relationship to the face of its companion main roll this adjustment can safely be made only when the mill is idle. Under previous conditions, when a workpiece enters the mill all clearances among the bearing and housing screw members

of the main rolls will be taken up by a spread to that amount at the main rolls and, moreover, whatever flexibility there may be in the main parts of the mill framework will reflect a further spread of the main rolls. Whatever the total of this main roll spread is will have added thereto the give arising from similar sources in the companion guide disc mountings. Thus it can be seen that the give of guide discs and main rolls have an additive effect in creating a widening of the gaps between the main roll faces and the guide disc lips, which gaps, as learned in practice, should be no more than to permit guide disc rotation, whether the mill is under load or is idle, with but enough clearance at the companion roll face as to insure freedom from contact therewith.

In the cross-roll and guide disc rolling procedure, each of the two main rolls feeds the metal being rotatively worked to the lip of a guide disc that is set in a manner as directly as possible to receive and then divert the flow of metal crosswise of the guide disc groove. As each main roll feeds directly to its own guide disc, that guide disc is referred to herein as being the companion disc of its respective main roll or vice versa. Pressures tending to spread the main rolls in the type of mill herein dealt with exceed what might ordinarily be expected and, moreover, vary in the course of the working of a workpiece even when the workpiece is uniformly heated throughout its extent. This condition arises from the novel ability of the cross-roll guide-disc type of mill to correct inequalities in wall thicknesses of the workpiece being worked. It is obvious that at a position in a workpiece where such inequalities are greatest, the pressure tending to spread apart the main rolls must likewise be greatest, but quite contrary to what might be expected, the spreading tendency at places along the workpiece where the piece has a measure of eccentricity of bore which is greater than at other places, will reflect a pronounced spreading tendency at the main rolls. This creates a substantial additional tendency locally to spread the main rolls, which to that degree increases the wall thickness of the tube at such places although still keeping the wall thickness uniform cross-sectionwise.

The cross-roll and guide disc type of mill is generally recognized as affording the only seamless tube making procedure possessing the ability to correct gauge inequalities. The preloading of the working members as herein described enhances that ability.

A full understanding of the invention can best be given by a detailed description of an illustrative embodiment of the invention, and such a description will now be given in connection with the accompanying drawings showing a tube elongating cross-rolling mill equipped with guide discs and having preloading means in accordance with the invention.

In said drawings—

Fig. 1 is a partial view looking toward the entrance end of the mill sectioned on the plane of line 1—1 of Fig. 2;

Fig. 2 is a section taken on line 2—2 of Fig. 1;

Fig. 3 is an enlarged sectional view of the lower guide disc and its mountings and adjacent parts; and

Fig. 4 is a still further enlarged sectional detail view taken on line 4—4 of Fig. 3.

The drawings show a tube-elongating mill of the kind disclosed in the S. E. Diescher Patent

1,870,209. The mill has a pair of helically acting cross-rolls 10 in the pass between which a tubular blank 11 which is being reduced is rotated and given a helical advancing movement on a mandrel 12, and a pair of peripherally grooves guide discs 15 mounted on opposite sides of the pass line with their axes extending at, or approximately at, right angles to the pass line and the rims of the discs extending between the cross-rolls to engage the tubular blank.

The cross-rolls are skewed, being mounted with their axes inclined to each other and to the line of feed of the blank between them. Their suitably driven shafts 16 are journaled in bearing blocks 17 slidably mounted in the mill frame 20 and adjustably moved toward or from each other by means of screws 21. The guide discs, as shown in Fig. 3 for the lower disc, are each carried by a shaft 22 journaled in a split bearing shell, or housing, 23, the shaft being driven through universal coupling 24 to rotate the disc in the direction of longitudinal movement of the blank or workpiece at a peripheral speed materially in excess of the longitudinal movement of the workpiece. Each disc is detachably but rigidly mounted on a flanged hub 25 at the overhanging inner end of its shaft 22.

The guide discs are spaced apart sufficiently to permit the tubular blank, under the wall-reducing pressure of the cross-rolls, to bulge somewhat away from the mandrel as described in the S. E. Diescher Patent 1,870,209, and as shown in Fig. 3 of the drawings hereof. The peripheries of the discs are grooved, or concavely curved transversely, for engaging the bulging wall of the blank as it comes from one of the cross-rolls and deflecting and directing it toward the other cross-roll, and each disc is set with its rim closely spaced from the cross-roll which rotates the tubular blank toward the disc, as shown and described in the S. E. Diescher Patent 1,951,348.

The bearing shells 23 are adjustable longitudinally to bring the rims of the guide discs into desired relationship with the cross-rolls. As shown in Fig. 3 for the lower guide disc, the shaft 22 of each disc is mounted within its shell 23 by a roller bearing 30 adjacent the overhanging disc and a roller bearing 31 near the other end of the shell, these bearings taking the radial load on the shaft, and by a double ball bearing 32 to take the longitudinal thrust on the shaft. The shell 23 is slidably mounted for longitudinal movement on a vertically adjustable frame or stool 33. Extending from the shell 23, is a lug 35 from which a bar 36 extends parallel with the shaft, the bar having a threaded portion which is engaged by a worm nut 37 rotatably mounted and held against axial movement in the frame and which is rotated by a worm 38 turned by means of a hand wheel, not shown, or otherwise. By this worm and screw rigging the guide disc may be adjusted axially as desired.

The endwise thrust on each disc shaft is thus taken by the ball bearings 32 and transferred to the shell 23 and thence through screw bar 36 and worm nut 37 to the frame 33. There will be some yield and clearance to take up in these parts under load. This results, as stated, in a slight weaving of the discs across the pass between the roll-faces. To take up these clearances and to preload the yielding parts to the extent of the longitudinal movement of the guide discs under load, the mill is provided with thrust units which act directly against the overhanging ends 75 of the disc shafts.

The preloading thrust unit for the shaft of the lower guide disc is shown in section in Fig. 3, and the mill shown has a similar construction for the upper disc shaft. Referring especially to Fig. 3, a hollow spindle 40 is mounted, in line with the disc shaft 22 and on the other side of the disc, within a split bearing shell, or housing, 41 which is slidably mounted for longitudinal movement on the frame 33. The spindle 40 is mounted by means of longitudinally spaced roller bearings 42 and 43 and a ball thrust bearing 44. Supported to be capable of limited universal movement within the hollow spindle 40, is a thrust spindle 50 having spherically curved ends. The outer end of this thrust spindle 50 seats against a cupped seat 51 fixed in the outer end of hollow spindle 40 and which is spherically curved to fit the end of spindle 50. The inner end of spindle 50, when the shell 41 is moved in to operative position, bears against a cupped end piece 52 at the disc-carrying end of shaft 22, the spindle engaging face of this end piece being spherically curved to fit the end of the spindle. The end piece 52, instead of being formed integral with the shaft 22 or hub 25, is most desirably a separately formed piece detachably secured to the end of the shaft or hub.

The thrust spindle 50 is of less diameter than the bore of hollow spindle 40 so that the thrust spindle is free to float universally inside the hollow spindle in the event of slight mis-alignment of the end of shaft 22 and spindle seat 51. The end of the thrust spindle is keyed to the cupped end piece 52 to cause the spindle to rotate with the disc shaft. As shown, a key 53 is set into and secured in a slot in the end of the spindle and also enters a slot in the cupped end piece, there being clearance between the key and the slot in the end piece so that the key shall not interfere with any needed universal movement of the spindle over a range sufficient to take care of any likely misalignment. At the outer end of the hollow spindle 40, there is a key 54 seated in slots in the hollow spindle and in the cupped seat 51 and in the end of the thrust spindle, whereby the hollow spindle is caused to rotate with the thrust spindle in synchronism with the disc shaft 22. This key also is loosely fitted in the slot in the thrust spindle so as not to interfere with the universal movement of the spindle.

The bearing shell 41 might be moved longitudinally in its seat on the frame 33 by any suitable force-applying means. As shown, it is moved by a worm and screw rigging similar to that provided for the shells 23, the shell 41 carrying a lug 55 from which a bar 56 extends parallel with the spindle 40, this bar having a threaded portion which is engaged by a worm nut 57 rotatably mounted and held against axial movement in the frame 33 and which is rotated by a worm 58 turned by a hand wheel, not shown, or otherwise.

To preload the disc shaft, the bearing sleeve 41 is moved by means of the worm and screw rigging to bring the end of thrust spindle 50 into engagement with the cupped face of block 52, and then further moved and forced inward to force the end of the thrust spindle against the block 52, thereby to preload the entire disc shaft bearing assembly, including its worm and screw rigging and the mounting parts including frame 33, and at the same time also preloading the thrust rigging itself and its worm and screw operating means.

Obviously, means other than the worm and

screw rigging shown might be provided for forcing the thrust spindle assembly inward to apply the preloading pressure to the disc shaft, and the invention is not to be limited to the use of such or other mechanical forcing means. Such means has the recommendation of simplicity as compared to a suitable hydraulic rigging, with which, however, the extent of the preloading thrust could be more definitely fixed and maintained.

10. The operating means provided for moving the shaft bearing shells 23 for adjusting the position of the discs with relation to the rolls, and for moving the thrust spindle bearing shells 41 for applying preloading pressure to the disc shafts, serve also, in the construction shown, for separating the bearing shells for the purpose of changing discs, the end pieces 52 being removed and the lower disc-carrying frame being lowered for this purpose and the upper disc-carrying frame raised.

20. For loosely retaining each of the thrust spindles 50 in its hollow spindle 40 at times when one of the disc shaft mountings and the opposing thrust spindle mounting are moved apart for disc changing, a threaded plug 60 is provided which is screwed into the wall of the hollow spindle and projects down into a short slot in the thrust spindle.

25. Although the axial thrust exerted on the guide discs by the rapidly rotating workpiece is in opposite directions on the two discs, the preloading pressure may, as in the mill illustrated, be applied in the same direction to both disc shafts, since it is immaterial in which axial direction 30 the pressure is applied, so long as it is sufficient to take up the clearances and harmful yields in the mounting parts and the pressure applying means will hold against any counter-pressure in the operation of the mill.

35. As stated, it is desirable that, in addition to the preloading of the guide discs, preloading means are provided also for the cross-rolls. Such means are shown in Figs. 1 and 2. As here shown, hydraulic jacks 70 are mounted between the bearing blocks 17 of the two rolls and act to press the blocks apart with a force sufficient to take up all clearances in the screw rigging of the blocks and all harmful yields in the frame 20 under the operating pressure on the rolls. Bearings for the roll shafts are built under close tolerances not requiring to be taken up by preloading, the preloading of the bearing blocks and frame being all that is required.

40. Four of the jacks 70 are provided, one at the top and one at the bottom of the bearing blocks on the entry side of the mill, and one at the top and one at the bottom of the bearing blocks on the exit side of the mill. Each jack, as shown and most desirably, is formed by a block bored to provide a hydraulic cylinder closed at one end and to contain a plunger suitably packed, as by means of a cup packing at its fluid pressure end as is usual for a single acting plunger. Each cylinder has an inlet opening 71 at its inner end to which pressure fluid is supplied through suitable connections. The jacks are held in place by the water shields 72 which have holes bored through them corresponding to the diameters of the cylinder base and the plunger end. The cylinder assemblies must be readily removable, for otherwise renewal of rolls may be delayed.

45. It is to be understood that the invention is not to be limited to tube elongating mills of the kind illustrated and to which the foregoing description has been largely confined, but that pre-

loading means according to the invention may be applied to other guide disc cross-rolling mills of the kind referred to, whether for operating on tubular or solid workpieces, including piercing mills for producing tubular blanks, or hollows, from solid cylindrical workpieces. It is to be understood, further, that the invention is not to be limited to the preloading means shown in the drawings, but that it includes changes and modifications thereof within the claims.

What is claimed is:

1. In a cross-rolling mill having a pair of helically acting skewed reducing rolls and a rotary guide disc mounted on a driven shaft to bear peripherally on the workpiece between the reducing rolls, preloading means for applying to the guide disc axially thereof pressure sufficient to take out clearances in and harmful yields of the shaft mounting parts.
2. In a cross-rolling mill having a pair of helically acting skewed reducing rolls and a rotary guide disc mounted on a driven shaft to bear peripherally on the workpiece between the reducing rolls, preloading means for applying to the shaft of the guide disc axially thereof pressure sufficient to take out clearances in and harmful yields of the shaft mounting parts.
3. In a cross-rolling mill having a pair of helically acting skewed reducing rolls and a rotary guide disc mounted on a driven shaft to bear peripherally on the workpiece between the reducing rolls, preloading means for applying to the shaft of the guide disc axially thereof pressure sufficient to take out clearances in and harmful yields of the shaft mounting parts, said preloading means comprising a thrust member mounted for engagement with an end of the guide disc shaft and means for forcing the thrust member against the end of the shaft.
4. In a cross-rolling mill having a pair of helically acting skewed reducing rolls and a rotary guide disc mounted to bear peripherally on the workpiece between the reducing rolls with its rim closely spaced from the reducing roll which rotates the workpiece toward the disc; preloading means comprising a thrust member mounted for engagement with an end of the guide disc shaft and means for forcing the thrust member against the end of the shaft.
5. In a cross-rolling mill having a pair of helically acting skewed reducing rolls and a rotary guide disc mounted to bear on the workpiece between the reducing rolls, the guide disc being carried by the overhanging end of a shaft journaled within a longitudinally adjustable housing; preloading means comprising a thrust member mounted for engagement with the overhanging end of the guide disc shaft and means for forcing the thrust member against the end of the shaft.
6. In a cross-rolling mill having a pair of helically acting skewed reducing rolls and a rotary guide disc mounted to bear on the workpiece between the reducing rolls, the guide disc being carried by the overhanging end of a shaft journaled within a longitudinally adjustable housing mounted on a vertically adjustable frame; preloading means comprising a thrust member mounted for engagement with the overhanging end of the guide disc shaft and means for forcing the thrust member against the end of the shaft.
7. In a cross-rolling mill having a pair of helically acting skewed reducing rolls and a rotary guide disc mounted to bear on the workpiece

- between the reducing rolls, the guide disc being carried by the overhanging end of a shaft journaled within a longitudinally movable housing, and having means for moving said housing longitudinally for adjustably positioning the guide disc with relation to the reducing rolls and for withdrawing the shaft for disc changing, said means comprising a screw bar secured to said housing and a worm nut on said screw bar and held against axial movement by the mill frame and a worm for turning said nut; preloading means comprising a thrust member mounted for engagement with the overhanging end of the guide disc shaft and means for forcing the thrust member against the end of the shaft.
8. In a cross-rolling mill having a pair of helically acting skewed reducing rolls and a rotary guide disc mounted to bear on the workpiece between the reducing rolls, the guide disc being carried by the overhanging end of a shaft journaled within a longitudinally adjustable housing; preloading means comprising a thrust spindle for engaging the overhanging end of the guide disc shaft, a hollow spindle in which the thrust spindle is housed free to float universally between a seat at the outer end of the hollow spindle and the end of the shaft, a longitudinally movable housing in which said hollow spindle is journaled, and means for forcing said housing inward thereby to force the thrust spindle against the end of the shaft.
9. In a cross-rolling mill having a pair of helically acting skewed reducing rolls and a rotary guide disc mounted to bear on the workpiece between the reducing rolls, the guide disc being carried by the overhanging end of a shaft journaled within a longitudinally adjustable housing; preloading means comprising a bearing housing longitudinally movable in alignment with the housing of the guide disc shaft, a hollow spindle journaled within said housing, a thrust spindle within the hollow spindle of a diameter less than the diameter of the bore of the hollow spindle, the inner end of the thrust spindle being spherically curved to engage a correspondingly but oppositely spherically curved seat at the end of the guide disc shaft and being loosely keyed thereto to turn therewith, and the outer end of the thrust spindle being spherically curved to seat against a correspondingly but oppositely spherically curved seat at the outer end of the hollow spindle, and the hollow spindle being loosely keyed to the thrust spindle to turn therewith, whereby the thrust spindle is free to float universally within the hollow spindle to accommodate itself to any slight mis-alignment between the shaft and the hollow spindle, and means for forcing said bearing housing inward, thereby to force the thrust spindle against the end of the shaft.
10. In a cross-rolling mill having a pair of helically acting skewed reducing rolls, a driven shaft extending transversely of the pass line of the mill, bearing means for said shaft, a guide disc mounted on the inner end of said shaft beyond said bearing means and extending between the reducing rolls to bear on a workpiece being advanced by the rolls, means for moving said bearing means and shaft longitudinally for adjustably positioning the guide disc with relation to the reducing rolls and for moving said bearing means to withdraw the shaft for disc changing, and preloading means comprising a thrust spindle mounted in alignment with said shaft for engagement with the overhanging end thereof

and for rotation therewith, the shaft-engaging end of said spindle being free to move laterally with the end of the shaft, and means for forcing said thrust spindle against the end of the shaft.

11. Apparatus as claimed in claim 10, in which the overhanging end of the shaft is provided with a detachably secured end piece against which the thrust spindle bears.

12. In a cross-rolling mill having a pair of helically acting skewed reducing rolls and a pair of rotary guide discs mounted on driven shafts on opposite sides of the reducing rolls to bear on the workpiece between the reducing rolls, pre-loading means for applying to each of the guide disc shafts axially thereof pressure sufficient to take out clearances in and harmful yields of the shaft mounting parts.

13. In a cross-rolling mill having a pair of helically acting skewed reducing rolls and a pair of rotary guide discs mounted on opposite sides of the reducing rolls to bear on the workpiece between the reducing rolls, each guide disc being carried by the overhanging end of a shaft journaled within a longitudinally adjustable housing; preloading means for each guide disc comprising a thrust member mounted for engagement with the overhanging end of the guide disc shaft, and means for forcing the thrust member against the end of the shaft.

14. In a cross-rolling tube-reducing mill having a pair of helically acting skewed rolls for reducing the wall thickness of a tubular blank on a mandrel and a pair of rotary guide discs mounted on opposite sides of the reducing rolls to bear on the tubular blank between the reducing rolls, the guide discs being spaced apart to permit the tubular blank to bulge somewhat away from the mandrel and each disc having its rim closely spaced from the reducing roll which rotates the tubular blank toward the disc; preloading means for each guide disc comprising a thrust member mounted for engagement with an end of the guide disc shaft and means for forcing the thrust member against the end of the shaft.

15. In a cross-rolling mill having a pair of helically acting skewed reducing rolls and a rotary guide disc mounted on a driven shaft to bear peripherally on the workpiece between the reducing rolls, preloading means for applying to the guide disc axially thereof pressure sufficient to take out clearances in and harmful yields of the shaft mounting part, and preloading means for

applying to the reducing rolls transversely of the axes thereof pressure sufficient to take out clearances in and harmful yields of the roll mounting parts.

16. In a cross-rolling tube reducing mill having a pair of helically acting skewed rolls for reducing the wall thickness of a tubular blank on a mandrel, the rolls being mounted with their shafts journaled in adjustable bearing blocks, and a pair of rotary guide discs mounted on opposite sides of the reducing rolls to bear on the tubular blank between the reducing rolls, the guide discs being spaced apart to permit the tubular blank to bulge somewhat away from the mandrel and each disc having its rim closely spaced from the reducing roll which rotates the tubular blank toward the disc; preloading means for applying to each of the guide disc shafts axially thereof pressure sufficient to take out clearances in and harmful yields of the shaft mounting parts, and preloading means for applying to the reducing rolls transversely of the axes thereof pressure sufficient to take out clearances in and harmful yields of the roll mounting parts.

17. In a cross-rolling mill having a pair of helically acting skewed reducing rolls each journaled in two spaced adjustable bearing blocks; preloading means for applying to each of said bearing blocks at points above and below the pass line and between opposing pairs of bearings pressure transversely of the axes of rotation of the rolls sufficient to take out clearances in and harmful yields of the roll mounting parts.

18. In a cross-rolling mill having a pair of helically acting skewed reducing rolls each journaled in two spaced adjustable bearing blocks; preloading means comprising a plurality of fluid pressure jacks mounted between the bearing blocks at one end of the rolls and a plurality of fluid pressure jacks mounted between the bearing blocks at the other end of the rolls for applying to the bearing blocks at points above and below the pass line pressure sufficient to take out clearances in and harmful yields of the roll mounting parts.

19. In a cross-rolling mill having a pair of helically acting skewed reducing rolls each journaled in two spaced adjustable bearing blocks; preloading means as claimed in claim 18 in which the fluid pressure jacks are mounted in openings in water shields mounted to shield the roll bearings.

SAMUEL E. DIESCHER.
